UNITED STATES PATENT OFFICE.

SIMON W. FARBER, OF BROOKLYN, NEW YORK.

DESIGN FOR A METAL CASSEROLE HOLDER OR SIMILAR ARTICLE.

Application filed February 16, 1925. Serial No. 12,395. Term of patent 7 years.

To all whom it may concern:

Be it known that I, SIMON W. FARBER, a citizen of the United States of America, residing at Brooklyn, in the county of Kings, city and State of New York, have invented a new, original, and ornamental Design for Metal Casserole Holder or Similar Article, of which the following is a specification, reference being had to the accompanying drawing, forming a part thereof.

In the drawing—

Fig. 1 is a perspective view of a holder showing my improved design.

Fig. 2 is an enlarged detail view of the ornamentation on the holder in question.

I claim:

The ornamental design for a metal casserole holder or similar article substantially as shown.

SIMON W. FARBER.
